US0D1074730S

(12) **United States Design Patent** (10) Patent No.: **US D1,074,730 S**
(45) Date of Patent: ** May 13, 2025

(54) **DISPLAY SCREEN OR PORTION THEREOF WITH A GRAPHICAL USER INTERFACE**

(71) Applicant: **Beijing Zitiao Network Technology Co., Ltd.**, Beijing (CN)

(72) Inventors: **Ling Qiu**, Beijing (CN); **Yichen Li**, Beijing (CN); **Zhaoyuan Peng**, Beijing (CN); **Jian Sun**, Beijing (CN); **Sisi Pan**, Beijing (CN)

(73) Assignee: **Beijing Zitiao Network Technology Co., Ltd.**, Beijing (CN)

(**) Term: **15 Years**

(21) Appl. No.: **29/924,959**

(22) Filed: **Jan. 22, 2024**
